UNITED STATES PATENT OFFICE.

JOSEPH VERNACI, OF BROOKLYN, AND ANTONIO CAROLLO, LUIGI CAROLLO, AND SALVATORE CAROLLO, OF LONG ISLAND CITY, NEW YORK.

MACARONI DRIER.

Application filed September 18, 1923. Serial No. 663,393.

To all whom it may concern:

Be it known that JOSEPH VERNACI, a subject of the King of Italy, residing at Brooklyn, county of Kings, and State of New

5 York, and ANTONIO CAROLLO, LUIGI CAROLLO, and SALVATORE CAROLLO, subjects of the King of Italy, residing at Long Island City, in the county of Queens and State of New York, have invented certain new and useful

10 Improvements in Macaroni Driers, of which the following is a specification.

This invention relates to macaroni driers of the type in which air is circulated through the macaroni for the purpose of 15 removing excess moisture and improving the quality of the macaroni.

It is one of the objects of the invention to provide a drier which will dry the macaroni uniformly and quickly without causing 20 cracking or the like in the macaroni.

Another object is to provide a macaroni drier consisting of a plurality of drying chambers and means to control the circulation of air therethrough whereby the air 25 may be circulated through any one chamber while the circulation through the remaining chambers is cut off.

Another object of the invention is to provide a macaroni drier consisting of two or 30 more drying chambers in which one chamber may be used for drying while the macaroni is being changed in the other and vice versa, the same circulating means being used for both chambers.

35 Other objects and advantages will appear as the description of the invention proceeds.

Referring now to the drawings which illustrate a preferred embodiment of the invention.

40 Figure 1 is a side view of the drier, with certain parts shown in dotted lines to indicate various positions thereof.

Fig. 2 is a plan view with parts broken away.

45 Fig. 3 is a sectional view on the line 3—3 of Fig. 1.

Fig. 4 is a detail sectional view of the drawers.

In the embodiment illustrated the drier

comprises a pair of drying chambers 1 and 2 connected by an intermediate fan chamber 3 of smaller dimensions than the driers 1 and 2.

As the drying chambers 1 and 2 are substantial duplicates, a detailed description of 55 only one will be given, together with such reference to the other as may be necessary to explain the operation of the device.

The chamber 1 for example is of rectangular construction having a rear wall 4, 60 side walls 5 and a front wall 6. The front wall 6 has a number of openings 6^a therein to provide places for the drawers 8 to be slid into and out of the chambers, suitable supports 20 being provided upon the rear wall 4 and side walls 5, and upon an open frame work 21 inside the chamber to support the drawers in the chamber. As illustrated each chamber is provided with three tiers of drawers with six drawers to a tier 65 70 but the number of tiers and drawers can obviously be changed according to the style and size of the drier.

The rear wall 4 and the front wall 6 are each provided with a longitudinal opening 7 near the top of the chamber and above the drawers 8, each having a suitable door 7^a for closing the opening. The doors may be swung upon the hinges 8^a and provided with latches 9 for holding the same closed. 75 80

An air circulating compartment 10 is provided below the drawers 8, which communicates with fan chamber 3 through the opening 11. Doors 12 are provided for controlling the communication between the compartment 10 and the chamber 3, suitable means being provided to hold the doors in open or closed position as desired. 85

The fan chamber 3 houses the fan 13 which is driven by suitable driving mechanism 14 of a reversible type to effect a proper circulation of air through the drying chambers. The top of the chamber 3 at either side of the fan is provided with a pair of hinged doors 15 and 16 through which the air drawn from the chambers 1 or 2 is discharged. The front of the chamber 3 is also provided with doors 17 hinged at 18 90 95

and provided with a latch 19, whereby access is had to the interior of chamber 3 for opening or closing the doors 12 and for other purposes.

5 As illustrated in Figs. 2 and 4 the drawers consist of suitable side walls 22 and have a screen bottom 23 to permit free circulation of the air through the macaroni therein. The walls 22 are rabbeted at 24 to provide 10 an easy means for fastening the screens 23 in the drawers. Handles 25 are provided for manipulating the drawers.

In the operation of the drier as illustrated in Fig. 1 the macaroni is placed in the 15 drawers 8, and the drawers slide into chambers 1, the doors 7^a at the front and back of the chamber are opened and the fan 13 is started to draw the air through the openings 7, down through the macaroni in 20 drawers 8, through compartment 10, opening 11 and out through the door 16 in the chamber 3 as indicated by the arrows.

During the drying of the macaroni in the chamber 1 the macaroni being made in the 25 factory can be placed in the chamber 2. The circulation of the air through chamber 2 during this period is prevented by the closed doors 12 and 7^a.

When the macaroni in the chamber 1 is 30 dried sufficiently, the fan is stopped, and the doors 7^a and 12 of the chamber 1 and door 16 of chamber 3 are closed, whereupon the dried macaroni can be removed and the drawers refilled with undried macaroni.

35 During the refilling of the drawers in the chamber 1, the macaroni placed in the chamber 2 may be dried by opening the doors 7^a, 12 and 15, and starting the fan in reverse direction to draw the air down through the 40 chamber 2 and out through the opening controlled by door 15.

The size of the drier and the rate of drying 45 may be coordinated with the output of the factory so that during the time required to dry the macaroni in one chamber, the other chamber may be unpacked and refilled, the chambers being adapted to hold all the macaroni produced in the meantime so that there is always one chamber in the process 50 of being dried and another in the process of being unpacked and refilled.

By this arrangement the output of the 55 factory can be made continuous as it is never necessary to stop production and wait until the drying is finished in order to have a place for the disposal of the formed macaroni.

60 By the use of this drier it has been found that the macaroni may be safely dried in as little a time as one hour without causing cracks therein, that the drying is much more uniform than in the pressure driers where the part of the macaroni near the fan is subjected to a strong blast of air and that remote from the fan to a weakened air blast, 65 and that the suction current does not blow

the macaroni about in the chambers as the pressure driers sometimes do.

While the invention has been described with reference to two drying chambers it is obvious that the principles of the invention may be applied to a drier with a plurality of chambers and that various other modifications and changes may be made without departing from the spirit of the invention as defined in the claims, which are intended to claim the invention as broadly as the state of the prior art will permit.

What we claim is:

1. In a drier for macaroni or the like the combination of a plurality of drying chambers, an intermediate chamber communicating therewith, suction means in the intermediate chamber, and doors between the drying chambers and the intermediate chamber to permit the suction means to circulate the drying medium through one chamber while circulation through the other chamber is prevented.

2. In a drier for macaroni, or the like, the combination of a pair of drying chambers, 90 and an intermediate chamber having openings in the drying chambers, a fan in the intermediate chamber, means to close said openings to permit the fan to circulate the drying medium through one chamber and 95 exhaust it through the intermediate chamber and means to prevent the circulation of the drying medium through the other chamber, said means and said fan being reversible to cause the medium to circulate through either 100 chamber.

3. In a drier for macaroni or the like, the combination of a pair of drying chambers, a fan chamber connecting the drying chambers and communicating therewith a reversible fan in said chamber and means to control the communication so that air may be circulated through either chamber while circulation through the other chamber is 105 prevented.

4. In a drier for macaroni or the like, a pair of drying chambers having openings at one extremity thereof, an intermediate fan chamber communicating with the drying chambers near the other extremity thereof, and means to draw air from the openings through either drying chamber and discharge it from the intermediate chamber.

5. In a drier for macaroni or the like, the combination of a pair of drying chambers having openings therein, an intermediate chamber, communicating with each drying chamber, means to stop communication between the intermediate chamber and either drying chamber, a fan in the intermediate chamber and a door opening to the atmosphere at each side of the fan, whereby air may be drawn through either of the drying chambers and discharged through the intermediate chamber, while circulation of air 120 125 130

through the other drying chamber is prevented.

6. In a drier for macaroni or the like, the combination of a drying chamber having openings near the top thereof, a fan chamber communicating with the drying chamber near the bottom thereof, and means to draw air through the openings, downward through

the macaroni or the like in the drying chamber and out at the bottom of the chamber. ¹⁰

In testimony whereof we affix our signatures.
